CLAMPING DEVICE

Clyde N. Stover, Towson, Md., assignor to Western Electric Company, Incorporated, New York, N. Y., a corporation of New York

Application July 11, 1942, Serial No. 450,621

6 Claims. (Cl. 24—115)

This invention relates to article clamping devices and particularly to devices for clamping elongated articles, such as cable cores and the like, in a desired position while work is being performed thereon.

In the manufacture of paper insulated lead sheathed cables employed for communication purposes, it is customary to open up sections of the cable cores and to transpose the wires of the several pairs making up the core. In performing this operation, a section of the cable core is preferably clamped to a bench to prevent extensive movement thereof while the individual conductors are being severed, transposed and brazed.

Formerly metal clamps were used to secure the cable core to a bench and a plurality of bushings had to be provided for each clamp to permit the clamps to be used upon cable cores of different diameters. Aside from the fact that the metallic clamps sometimes damaged the cable cores, the necessity of stocking a large number of bushings of various sizes involved a considerable investment in small items and required the provision of storage space for the unused bushings. Furthermore, the changing of the bushings to accommodate different sized cable cores consumed valuable time.

The object of this invention is to provide simple, inexpensive and effective article clamping devices that may readily accommodate articles of various sizes.

In accordance with one embodiment of the invention, there is provided an elongated article gripping member made of a flexible material, such as canvas, which is fixed at one end and which is provided with a slot extending transversely across a portion thereof. In using this device, a cable core, or like elongated element, is placed transversely across the gripping member, and the free end of the gripping member is passed over the cable core, through the transverse slot and under the cable core. Means are also provided for engaging the free end of the gripping member and pulling it away from the fixed end thereof until the gripping member has firmly grasped the cable core. A suitable fastening means is supplied to secure the several elements of the device in the latter position.

A clear understanding of the invention may be had from the following detailed description of a specific embodiment of the invention, when read in conjunction with the annexed drawing, in which

Fig. 1 is a top plan view of a clamping device embodying the invention;

Fig. 2 is an end elevation thereof; and

Fig. 3 is a fragmentary sectional view thereof taken on line 3—3 of Fig. 1.

Referring now to Fig. 1 of the drawing, the clamping device illustrated therein comprises a base plate 10, to one end of which is secured an elongated article gripping member 11, preferably made of a flexible fabric such as canvas. The end of the gripping member 11 is fastened to the base plate 10 by means of a strap 12 and screws 13—13. The base plate 10 may be secured to a shop bench or other support by means of lag bolts 14—14, or the like. The article gripping member 11 is provided with a transverse slot 15 through which an elongated tongue shaped portion 16 of the gripping member may freely pass. A ring 18 is secured to the free end of the tongue shaped portion 16 by means of a loop 19.

Adjacent to the end of the base plate 10 opposite the strip 12 is an arm 21 pivotally mounted upon a post 22 extending upwardly from the base plate 10. The arm 21 extends upwardly as at 23 and then outwardly, as shown in Fig. 2, and a handle 24 is provided upon the outer end of the arm 21. The arm 21 is also provided with a cross arm 25 having an arcuate slot 26 formed therein, which is positioned directly above a post 28 secured to the base plate 10. A hand wheel 30 has a threaded stud 31 formed thereon which passes through the slot 26 and is screwed into a threaded bore 29 formed in the post 28. When the hand wheel 30 is tightened sufficiently, a shoulder 33 thereon engages the cross arm 25 and securely fastens the arm 21 in any desired position. A stud 35 extends upwardly from the arm 21 and a semicircular lug 36 formed on one side of the arm 21 carries a stud 37 which is identical with the stud 35.

In the operation of the device, the article gripping member 11 is laid out flat upon the base plate 10, and a cable core 39, or other elongated article which it is desired to secure in a fixed position, is placed transversely across the gripping member 11, as shown in Fig. 1. The ring 18 is then passed around the cable core 39, down through the slot 15, and under the cable core (Fig. 3). The ring 18 is next pulled toward the arm 21 to cause the tongue shaped portion 16 of the gripping member 11 to be pulled through the slot 15. The arm 21 is then rotated in a clockwise direction, as seen in Fig. 1, until

the posts 35 and 37 reach a point adjacent to the ring 18, whereupon the ring 18 is hooked over one of these posts. The arm 21 is then rotated in a counter-clockwise direction, as seen in Fig. 1, until the gripping member 11 has firmly gripped the cable core 39, when the hand wheel 30 is turned to secure the elements in that position.

When the article gripping member is firmly secured in the position last described, this member exerts a firm gripping pressure upon the cable core 39 and prevents longitudinal or lateral movement thereof. Thus, the cable core is held firmly and splicing or other operations may be performed thereon without having the core slide about on the shop bench. While the gripping member 11 grips the cable core 39 firmly, it has no sharp edges or projections which tend to injure the insulation or any of the conductors making up the cable core, and thus the injuries which were sometimes caused by metallic clamps are eliminated by the use of this device. Obviously, two or more of these clamping devices may be used to secure an article in a desired position, and the device may be used in connection with articles other than cable cores, if desired.

It is apparent that the article gripping device constituting this invention may be used to accommodate cable cores or other articles of various sizes, from very small ones to extremely large ones. By selecting either the stud 35 or the stud 37 to be engaged by the ring 18, a considerable amount of latitude is permitted. Also the elongated arcuate slot 26 in the cross arm 25 and the hand wheel 30 permits the arm 21 to be secured in any one of a number of positions, any one of which may represent a cable core or other article of a different size.

The device is also not limited in its use to the securing of articles of circular cross section. The device may be used to secure articles of irregular cross section because the flexible gripping member 11 will accommodate itself to the contour of the articles. It may be desirable, especially when small cable cores or other articles are to be secured, to wrap the tongue shaped portion 16 of the gripping member 11 around the core more than once. This may be accomplished readily by passing the tongue shaped portion 16 around the article and through the slot 15 the desired number of times.

The specific embodiment of the invention which is shown in the accompanying drawing and described in the foregoing specification is merely illustrative of the invention, and various changes and modifications may be made therein without departing from the spirit and scope of the invention as defined in the annexed claims.

What is claimed is:

1. An article clamping device, which comprises a flexible article gripping member having one end thereof fixed and having a portion thereof formed into a loop in which an article may be positioned, and means for urging the free end of the gripping member away from the fixed end thereof to draw the gripping member tightly

around an article positioned in the looped portion thereof to firmly secure the article therein.

5 2. An article clamping device, which comprises a flexible article gripping member having one end thereof fixed and having a portion thereof formed into a loop in which an article may be positioned, means for engaging the free end of the gripping member and for urging said free end away from the fixed end thereof to draw the gripping member tightly around an article positioned in the looped portion thereof to firmly secure the article therein, and means for securing the several elements of the device in any one of a number of positions.

10 3. A cable core clamping device, which comprises an elongated flexible article gripping member having a transverse slot formed therein through which one end thereof may be passed to form an article gripping loop, means for securing the other end of the gripping member in a fixed position, and means for urging the free end of the gripping member away from the fixed end thereof to draw the gripping member tightly around an article positioned therein to firmly 15 secure the article.

20 4. A cable clamping device, which comprises an elongated flexible article gripping member made of a textile fabric, said member having a slot formed transversely thereof and having a tongue portion formed at one end thereof which may pass freely through the slot, means for securing the end of the gripping member opposite the tongue portion in a fixed position, means for engaging the free end of the gripping member and for urging said free end away from the fixed end thereof to draw the gripping member tightly around an article positioned therein, and means for securing said engaging and urging means in any one of a number of positions.

25 5. A cable core clamping device, which comprises a base member, an arm pivotally mounted thereon, a stud extending upwardly from the arm, means for securing the arm in any one of a number of positions, and an elongated fabric gripping member secured at one end to the base plate, the gripping member having a slot formed transversely thereof through which the free end thereof may be passed to form an article gripping loop and means on the free end of the gripping member for engaging the stud on the arm.

30 6. A cable core gripping device, which comprises a base member, an arm pivotally mounted near one end of the base member, which arm has a stud projecting upwardly therefrom and is provided with an arcuate slot, a post secured to the base plate and positioned beneath the slot, means extending through the slot and cooperating with the post for securing the arm in a predetermined position, an elongated fabric gripping member secured at one end to a part of the base member removed from the rotatable arm, which gripping member is provided with a transverse slot and a tongue portion which may pass freely through said slot, and means upon the free end of the gripping member for engaging the stud on the arm.
